CLAIM

The ornamental design for a two piece snowboard, as shown and described.

DESCRIPTION

FIG. 1 is a perspective view of a two piece snowboard showing my new design, the broken lines are for illustrative purposes only and form no part of the claimed design; FIG. 2 is a top side view thereof;

FIG. 3 is a right view thereof, the left side being a mirror reflection thereof;

FIG. 4 is a bottom view thereof;

FIG. 5 is a front view thereof; and,

FIG. 6 is a back view thereof.
